UNITED STATES PATENT OFFICE.

JOHN A. DAVIS, OF WASHINGTON, DISTRICT OF COLUMBIA.

DESIGN FOR A TALKING-MACHINE.

58,552.

Specification for Design.

Patented Aug. 2, 1921.

Application filed June 19, 1920. Serial No. 390,263. Term of patent 7 years.

To all whom it may concern:

Be it known that I, JOHN A. DAVIS, a citizen of the United States, whose post-office address is care of the United States Navy, Washington, District of Columbia, have invented a new, original, and ornamental Design for a Talking-Machine, of which the following is a specification, reference being had to the accompanying drawing, forming part thereof.

The figure is a perspective view of a talking machine, showing my new design, in which the turntable, the molding on the deck

upon which the turntable is mounted, the tempo control base and knob or adjusting screw, the molding around the tone arm base, the sound box, the start and stop button, and the needle cups have their peripheral edges sloping. In the embodiment of the invention illustrated in the accompanying drawing, these sloping edges are shown as straight, plain and unornamented bevels.

I claim:

The ornamental design for a talking machine, as shown and described.

JOHN A. DAVIS.
